MUFFLER

Guy M. Hartsock, South Bend, Ind., assignor, by
mesne assignments, to C. F. Burgess Laboratories, Inc., Madison, Wis., a corporation of
Delaware

Application December 5, 1930. Serial No. 500,155

6 Claims. (CL 137—160)

This invention relates to attachments for carburetors.

It is an object of the invention to eliminate sound vibrations from the air passing into a carburetor.

A further object resides in the filtering of air being fed to a carburetor to prevent the entrance into the carburetor of particles of dirt and the like which are suspended in the air.

Another object comprises the provision of means disposed on the air intake pipe of a carburetor which functions both as a muffler to deaden sound vibrations and as an air filtering means.

It is a still further object to provide air attachment for carburetors having means for associating the device with the air intake pipe of the carburetor, and having acoustic or sound absorbing material disposed within the device to permit passage of the air to the air intake pipe but being positioned to cause the inrushing air to impinge against the acoustic material for the absorption of sound vibration. The acoustic material is also arranged to baffle the passage of incoming air so as to effect a considerable area of contact of the air therewith whereby to effect a complete absorption of objectionable sound.

A specific object relates to a muffler to be disposed over an air intake pipe and having portions provided with sound absorbing material over their inner surfaces, and being spaced to define a passage through the muffler for incoming air, said muffler being provided with an air filtering element disposed within the air passage formed by the spacing of the sound absorbing portions. Other objects and features of the invention not expressed above will be disclosed in the detailed description of the invention and in the accompanying claims.

Referring to the drawing which is to be taken as illustrative only and which represents a preferred embodiment of the invention, there is shown a vertical sectional view of the novel muffler construction in assembled position on a carburetor air intake pipe.

A carburetor 10 is provided with a vertically disposed air intake pipe 11, having the usual throttle or butterfly valve 13 controlled by a lever 14. The invention is illustrated as applied to a carburetor of the downdraft type, but it will be evident that it may be applied with equal efficiency to various other types and designs of carburetor.

The novel muffler embodying the features of

the invention comprises an annular split resilient collar 15 adapted to be sprung over the upper portion of the air intake pipe. Collar 15 is formed with a horizontal circular flange 16 having removably secured thereon, as by attaching screws or the like, not shown, a horizontal circular member 17 which has a central aperture registering with the carburetor air intake opening. Member 17 is spaced from flange 16 by means of a spacing ring 18, for the reception of the lower ends of the legs of a bridge 19 between the flange 16 and the inner portion of the member 17, the lower ends of the legs abutting the inner surface of the ring 18.

Member 17 is formed with an upstanding integral peripheral flange 20 upon which is supported a frusto-conical shell 21, having attached thereto by means of split pins 22, on its inner surface, a layer of sound absorbing material 23 which extends downwardly about the inner surface of flange 20. Pins 22 are turned at their inner ends to hold the sound absorbing material in position, and shell 21 is formed with a central opening to permit free passage of air, the inner edge of the shell being turned at 24 to form a further securing means for the sound absorbing layer 23.

The shell 21 is provided at its outer periphery with a lip 24 adapted snugly to overlap the upper portion of flange 16 to hold the shell securely in place, and it is further provided with an indented circumferential right angular groove 25 which receives a vertically disposed rigid reticulated cylinder 26. Upon the upper end of the screen is supported a frusto-conical shell or dome 27 formed at its outer circumferential edge with a horizontal circular flange 28 adapted to rest on the screen and having a lip 29 overlapping the upper end of the screen. The shell 27 is provided at its under surface with a layer of acoustic or sound absorbing material 30 secured thereto by means of split pins 31 having turned ends for holding the material 30 in place.

Through the opening in the center of the shell 27 and sound absorbing material 30 is extended a vertically disposed bolt 32 having an enlarged head at its upper end and which passes through the bridge 19 at its lower end. The lower end of the bolt is threaded for the reception of a nut 33 which is adjusted on the bolt to clamp the various parts of the muffler in position. The bolt 32 may be provided at its upper end with a slit 34 for the reception of a screw driver or the like.

Elements 15, 17, 21 and 27 are preferably

110

stamped or pressed sheet metal. The sound absorbing material 23 and 30 is preferably formed of a non-combustible material such as asbestos felt. Other sound-absorbing material, however, 5 of a fibrous, spongy or porous nature may be used; for example, steel, copper, or brass wool are suitable. The screen 26 preferably comprises several plies or laminae, but any suitable rigid material capable of filtering the incoming air 10 may be used in lieu thereof.

The various parts of the muffler assembly are securely held in position when the nut 33 is tightly screwed on to the bolt 32. The enlarged head of the bolt 32 clamps shell 27 down onto the 15 rigid screen 26 which in turn forces shell 21 against flange 20. The plate 17 must be independently secured to the flange 16. It will be seen from the above that the preferred form of 20 muffler comprises a lightweight construction free from rattles, squeaks and the like, and comparatively inexpensive to manufacture.

The operation of the device is as follows:

Air which is sucked into the carburetor intake 11 first passes through the filtering screen 26 25 whereby suspended dust, dirt and the like are removed, ingress of air being permitted through the screen about the whole periphery thereof. The rapidly moving stream of air is angularly baffled against the upper sound absorbing layer 30 30 by means of shell 21, and passes downwardly through the central opening in the shell 21, the turbulent flow of the baffled incoming air causing it to be contacted with the lower sound absorbing layer 23, the air, free from objectionable 35 vibration or hum, then passing downwardly into the air intake pipe 11.

The form of the invention above described is capable of considerable variation in design. For example, although the above described muffler 40 construction is exceedingly effective to remove sound from the incoming air, additional sound absorbing material may be disposed on the upper surface of the shell 21. This and like variations which do not depart from the concept of the 45 invention are considered to be within its scope.

I claim:

1. A muffler for use in connection with carburetors comprising a base member adapted to be secured to the air intake pipe of a carburetor 50 and provided with a central opening therein, a dome, means for rigidly securing the dome in spaced relationship with the base member, a centrally apertured intermediate member positioned

55

60

65

between the base member and the dome, peripheral means for spacing the dome circumferentially from the intermediate member to form an air passage, said means being composed of air permeable material throughout its periphery, the dome being provided with sound absorbing material on its inner surface, additional sound absorbing material being disposed on a surface of said intermediate member.

2. A muffler for use in connection with carburetors comprising a base member adapted to be secured to the air intake pipe of a carburetor, an intermediate centrally apertured member supported upon said base member and sloping upwardly from its outer periphery, a peripheral spacing member supported at its lower end upon the centrally apertured member and supporting a dome member at its upper end, the dome member and the intermediate member being spaced to form an air passage, and means acting in one direction on the dome member and in the opposite direction on the base member to clamp the members in rigid relationship.

3. The combination described in claim 2 in which the spacing member is composed of air permeable material about its periphery.

4. The combination described in claim 2 in which the dome member is provided at its inner surface with sound absorbing material.

5. The combination described in claim 2 in which the dome member is provided at its inner surface with sound absorbing material, additional sound absorbing material being disposed on a surface of said centrally apertured member.

6. A muffler for use in connection with carburetors comprising a base member adapted to be secured to the air intake pipe of a carburetor, an intermediate centrally apertured member supported upon said base member and sloping upwardly from its outer periphery, a peripheral spacing member supported at its lower end upon the centrally apertured member and supporting a dome member at its upper end, the dome member and the intermediate member being spaced to form an air passage, and means acting in one direction on the dome member and in the opposite direction on the base member to clamp the members in rigid relationship, the spacing member being composed of air permeable material, sound absorbing material being disposed on the inner surfaces of the dome member and of the intermediate member.
